UNITED STATES PATENT OFFICE

EDWARD B. ALLEN, NEWTOWN, CONNECTICUT

SEWING MACHINE

Application filed May 31, 1929. Serial No. 367,511.

This invention relates to sewing machines and, more particularly, to a sewing machine needle-bar vibrating mechanism having a rotary actuating crank receiving semi-rotational impulses from the main sewing machine shaft. The invention has for an object to provide mechanism for adjusting the operative radius of the needle-bar vibrating crank while the machine is in operation and which the crank is positively retained against displacement from adjusted position.

Another object of the invention is to provide mechanism for adjusting a crank to vary its operative radius relative to its supporting shaft, such mechanism being operative without stopping the shaft and being of a positive and preferably irreversible nature, so that the crank, for any position of adjustment, is positively held at the desired operative radius, from which it cannot move under centrifugal force or the forces of reaction to which the crank may be subjected at high operative speeds.

In the preferred embodiment of the invention there is provided a hollow shaft having at one end a head formed with ways in which a supporting plate for the crank-pin is mounted to slide transversely of the shaft's axis. Fitted within the shaft is a spindle having at one end an inclined portion fitting an inclined socket in the crank-supporting plate. The angle of inclination is such that endwise movement of the spindle will easily shift the crank-supporting plate along its slideway but any forces applied to the crank will be but feebly transmitted, if at all, to the spindle, the mechanism being practically irreversible.

The invention is designed more particularly for embodiment in the needle-bar vibrating crank-mechanism of a buttonhole sewing machine, such as disclosed in the patent to Allen, No. 1,629,139, of May 17, 1927.

Referring to the drawings, Fig. 1 is a side elevation of a buttonhole sewing machine embodying the invention. Fig. 2 is a top plan view of the bracket-arm of the machine. Fig. 3 is a reverse side elevation of the gearing shown in Fig. 1. Fig. 4 is a plan view of the gearing shown in Fig. 3. Fig. 5 is a

top-plan view of the head of the shaft carrying the needle-bar-vibrating crank-mechanism. Fig. 6 is a section on the line 6—6, Fig. 5, with the crank-pin at one extreme position of adjustment. Fig. 7 is a view similar to Fig. 6 but with the crank-pin at the other extreme position of adjustment. Fig. 8 is a bottom plan view of the crank-pin-supporting slide-plate and a fragment of the supporting head carrying a stop-screw, and Fig. 9 is a disassembled perspective view of the parts shown in Figs. 5 to 8, inclusive.

For the purposes of the present disclosure the invention is described as embodied in an automatic straight buttonhole sewing machine constructed substantially in accordance with the disclosure of the Allen Patent No. 1,629,139, and the patents referred to therein. The machine has the usual bed 1, standard 2, overhanging arm 3 and head 4. The stitch-forming mechanism comprises the reciprocating and laterally vibrating needle-bar 5 carrying the eye-pointed needle 6. The needle-bar 5 is journaled in the swinging gate 7 which is mounted on pivot-pins 8 and derives its vibratory movement from the main sewing shaft 9. The gate 7 is connected by means of the link 10 to the slotted arm 11 which is fulcrumed at 12 on the bracket-arm 3 and is connected by the link 13 to the crank-pin 14 fixed to the radially movable slide-plate 15 carried by the rotary guide-head 16 formed at the upper end of the hollow shaft 17 journaled vertically in the bracket-arm 3.

The guide-head 16 receives semi-rotational impulses through the train of gears 18 from the intermediate feed-actuating shaft 19 which carries the star-wheel 20 with which mesh the pins 21 carried by the hub of the bevel-gear 22 mounted on the bearing pin 23 and driven by the bevel-pinion 24 on the sewing shaft 9. The gear 22 is driven at half the speed of the shaft 9 and the gearing 18 is of such ratio that the guide-head 16 is given a half-rotation for each impulse of the star-wheel 20 received from one of the pins 21. The needle-bar is reciprocated by means of the usual crank 25 and link-connection 26 with the sewing shaft 9.

The hollow shaft 17 has slidably fitted

therein the vertical rod 27 having at its upper end the inclined portion 28 having flat, parallel and inclined, edge-faces 29 in sliding engagement with the similarly spaced parallel and inclined faces 30 provided by the plates 31, 32 mounted at the under side of the slide-block 15. The plate 31 is screwed fast in a fixed position to the slide-block. The plate 32 is secured to the slide-block by screws 33 which pass through enlarged holes 34 in the slide-block, giving clearance for a limited adjustment of the plate 32 relative to the plate 31 under the influence of the adjusting screw 35. The adjustment is so made as to eliminate lost-motion between the inclined end 28 of the rod 27 and the plates 31, 32, while retaining a free working fit. It will be understood that endwise movement of the rod 27 will shift the slide-plate 15 and crank-pin 14 diametrically of the guide-head 16 and vary the operative radius of the crank-pin. The movement of the slide-plate 15 is limited in one direction by the stop-plate 36 which is fixed to one end of the slide-plate 15 in position to engage the flat edge-portion 37 of the guide-head. The movement of the slide-plate in the opposite direction is limited by the stop-screw 38 which is threaded into the guide-head 16 and held in adjusted position by the locking screw 39. The head of the stop-screw 38 is in position to be engaged by the stop-shoulder 40 on the slide-plate. The angle of inclination of the end 28 of the rod 27 is preferably made small enough so that the motion is irreversible and that reactionary forces exerted on the crank-pin 14 will not shift the rod 27.

The rod 27 is formed at its lower end with a neck 41 embraced by the fork 42 at one end of the pin 43 journaled in the boss 44 at the free end of the lever 45 fulcrumed at 46 on the standard 2. Adjustably secured to the lever 45 by a screw-and-slot connection 47 is the follower 48 which is periodically engaged and lifted by the cam-plates 49 on the gear-wheel 50 fixed to the vertical shaft 51 carrying the main feed-wheel 52 which is connected as usual to shift the work-clamp 53. In the present machine the cam-plates 49 are arranged to increase the amplitude of vibration of the needle for barring both ends of a straight buttonhole.

The spring 46' acts upon the lever 45 to hold it pressed upon the faces of the gear-wheel 50 and cam-plates 49. The gear-wheel 50 on the feed-wheel shaft 51 is driven from the shaft 19 through the train of gears 54. The thickness of the cam-plates 49 is such as to impart the desired increased amplitude of vibration to the needle-bar for barring the ends of a buttonhole and the stop 38 is preferably adjusted to be engaged by the shoulder 40 on the slide-block 15 when the cam-plates 49 are under the follower 48. Hence, in the particular machine illustrated, means

additional to the irreversible character of the sliding connection between the rod 27 and crank-plate 15 are provided to positively lock the crank-plate in one extreme operative position.

The period of operation of the machine is controlled by the stop-motion device 55 preferably constructed substantially in accordance with the disclosure of the Allen and Myers copending application, Serial No. 75 272,416, filed April 24, 1928.

By virtue of the present improvement higher operative machine speeds may be safely used without danger of displacement of parts of the needle-bar vibrating mechanism by centrifugal or reactionary forces.

Having thus set forth the nature of the invention, what I claim herein is:

1. In a sewing machine, a needle-bar, a vibratory needle-bar gate, a rotary crank and connections for vibrating said gate, means for imparting operative impulses to said crank, means for changing the operative radius of said crank while the machine is in operation, and means for positively retaining said crank against displacement from its adjusted position.

2. In a sewing machine, a needle-bar, a vibratory needle-bar gate, a rotary hollow crank-shaft having a guide-head, a crank-pin slidably mounted on said guide-head, an operative connection between said crank-pin and needle-bar gate, a rod disposed within said hollow shaft and having an inclined end with parallel operative face-elements, spaced follower-elements rigid with said crank-pin and engaging the inclined operative face-elements of said rod, and means for shifting said rod endwise without stopping the machine.

3. In a sewing machine, a needle-bar, a vibratory needle-bar gate, a rotary hollow crank-shaft, a crank-pin carried by and movable laterally of the axis of said crank-shaft, an operative connection between said crank-pin and needle-bar gate, an endwise movable rod disposed within said hollow crank-shaft and irreversibly and positively connected to move said crank-pin in opposite directions laterally of the axis of said crank-shaft, and means for moving said rod endwise without stopping the machine.

4. In a sewing machine, a needle-bar, a vibratory needle-bar gate, a crank-shaft and means for imparting thereto semi-rotational impulses, a crank on said shaft, an operative connection between said crank and needle-bar gate, and means for changing the operative radius of said crank, said means including an endwise movable rod having spaced inclined operative face-elements, and follower means connected to said crank and in simultaneous working engagement with said inclined face-elements.

5. In a sewing machine, stitch-forming

- mechanism, work-shifting mechanism, a main-shaft connected to drive said mechanisms, a shaft having a guide-head, a slide mounted in said guide-head and having fixed and adjustable spaced follower-elements, a crank carried by said slide and connected to impart relative stitch-positioning movements to one of said mechanisms, an adjusting rod movable endwise of said shaft and having spaced operative face-elements in engagement with said follower-elements, and means for shifting said rod in opposite directions without stopping the stitch-forming mechanism.
- 6 5. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.
- 10 6. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.
- 15 7. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.
- 20 8. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.
- 25 9. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.
- 30 10. In a sewing machine, stitch-forming mechanism, work-shifting mechanism, a main-shaft, a crank-shaft connected to be driven by said main-shaft, a crank adjustably mounted on said crank-shaft and connected to impart relative stitch-positioning movements to one of said mechanisms, a crank-adjusting element, and an irreversible connection between said crank-adjusting element and said crank operative to positively move said crank toward or away from the axis of said crank-shaft without stopping the stitch-forming mechanism.

In testimony whereof, I have signed my name to this specification.

CERTIFICATE OF CORRECTION.

Patent No. 1,864,165.

June 21, 1932.

EDWARD B. ALLEN.

It is hereby certified that the above numbered patent was erroneously issued to the inventor said "Allen", whereas said patent should have been issued to The Singer Manufacturing Company, of Elizabeth, New Jersey, a corporation of New Jersey, as assignee of the entire interest in said invention, as shown by the records of assignments in this office; and that the said Letters Patent should be read with this correction therein that the same may conform to the record of the case in the Patent Office.

Signed and sealed this 4th day of October, A. D. 1932.

(Seal)

M. J. Moore,
Acting Commissioner of Patents.
